UNITED STATES PATENT OFFICE.

JOSEPH L. CASSELL, OF NEW YORK, N. Y.

MOTOR-VEHICLE SIGNAL.

Application filed November 15, 1928. Serial No. 319,688.

The objects of this invention are to provide a signal for automobiles and other motor vehicles which will derive its energy from the motor of the vehicle, without appreciably affecting the operation of the engine; which will furnish a clear sounding, far reaching signal of pleasing tone; which may be utilized to give various musical effects and which will be of relatively simple inexpensive construction readily applicable to present day motor vehicles.

The foregoing and other desirable objects are attained by certain novel features of construction, combination and relations of parts as hereinafter described and broadly claimed.

The drawings accompanying and forming part of the specification illustrate certain embodiments of the invention, but it should be understood that the structure may be modified as regards this disclosure without departure from the true spirit and basic scope of the invention.

Fig. 1 is a broken part sectional top plan view illustrating a four toned signal instrument as applied to an automobile; Fig. 2 is a broken side elevational view of the same; Fig. 3 is an enlarged part vertical sectional view of the instrument taken on substantially the line 3—3 of Fig. 4; Fig. 4 is a top plan view of the instrument illustrating particularly the valve mechanism; Fig. 5 is a further enlarged vertical sectional view as taken substantially on the plane of line 5—5 at Fig. 3; Figs. 6 and 7 are broken cross-sectional and part sectional side elevational views of a modified form illustrating electrical in place of the manual control first shown; Fig. 8 is a detached plan view of one of the double reed units.

The sounds for the signal are produced in the present invention by reeds set into vibration by flow of atmospheric air induced by suction of the intake of the engine. There may be one or a number of these reeds. In the present disclosure, there are four such reeds shown at 10, 11, 12, 13 having the fundamental frequencies of 435, 580.655, 731.580 and 870 respectively to give the notes middle A, D, F sharp and treble A, which particular notes can be combined for playing various

tunes and bugle and "Tally-Ho" calls. To gain the greatest volume of sound possible, these reeds are preferably double as indicated particularly in the detailed view, Fig. 8, each reed consisting of two like spring tongues. 55 These reeds may be of the "free" type shown, mounted to vibrate without contact in the reed throats 14, or if desired, they may be of the "striking" type employed in instruments of the wood wind type. 60

The reeds may be mounted in separate reed chambers 10^a, 11^a, 12^a, 13^a as in Figs. 1 to 5, or they may be mounted in a common manifold chamber 15 as in Figs. 6 and 7, the latter requiring only a single connection 16 to the 65 manifold and the former requiring in addition to the main connection 16 (Fig. 4) branches 13^b, 12^b, 11^b, 10^b to the respective reed chambers. As indicated in Figs. 4 and 5 these so-called branches to the several chambers are provided by forming passages 16 in the tops of the several chambers, connected 70 in series relation by the branch connections 12^b, 11^b and 10^b extending from the inner end of passage 16 in one chamber into the outer 75 end of passage 16 in the adjoining chamber. This serial arrangement provides in effect a common manifold by which any of the chambers may be connected to engine suction.

Valve means by which individual control 80 of the reeds may be effected is shown in Figs. 1 to 5 in the form of a slide valve 17 pivoted at 18 on top of each chamber and having a cavity 19 in the under-face of the same designed when the valve is shifted into the position of the second valve shown in Fig. 4, to establish communication between an upwardly opening passage 20 extending from 85 passage 16 and a passage 21 through the top of the reed chamber. 90

Wires 22 are shown connected with the valves and leading in the illustration to finger keys 23 mounted on the steering column or other convenient support. Springs 24 connected with the slide valves return them to 95 the position indicated in Fig. 5 when the finger keys are released, in which position the engine suction in the conduit ending at 20 is cut off by the valve. When however the valve is shifted, against the force of the 100

valve closing spring to the right in Fig. 5 and the pass 19 in the valve establishes communication between port 20 and the hole 21 in the top of the reed chamber, engine suction 5 will be applied to this chamber and the reed will be set into vibration.

To amplify the sounds generated by the reeds resonators are preferably employed. These resonators are shown as closed organ 10 pipes 10°, 11°, 12° and 13° supported with their open ends below the reeds and with the proper air coupling 25 between the reeds and the open ends of the pipes to effect the proper resonant relation. For this purpose, the pipes 15 may be mounted adjustably so that they can be set in this proper resonant relation, but it has been found most practical to determine this air coupling distance and then fixedly mount the pipes as by means of fastenings 20 such as indicated at 26 in a suitable frame or base 27.

The resonators preferably are of the same natural frequency as the reeds with which they cooperate, and similarly the reed chambers also bear a tuned relation to the reeds. 25 The latter effect may be obtained by making these reed chambers of stopped organ pipes similar to the stopped pipe resonators 10°, etc. With this tuned relation between the reeds, 30 reed chambers and resonators, the air drawn through the reeds causes alternate waves of rarification and condensation to travel in synchronism with the reed movements up and down the tuned pipes producing powerful, 35 but at the same time pleasing tone effects.

These sound effects may be still further strengthened and amplified if desired, by using a horn or horns in conjunction with the resonator or resonators, such as indicated at 40 28 in Fig. 3 where there is shown an exponential type horn attached to the resonator 13°, the closed end of the resonator pipe being shown as a flexible diaphragm 29 for vibrating the air column of the horn.

45 In use, the instrument has no apparent effect upon the motor, the latter furnishing an ample suction source unaffected by use of the device. At full open throttle when manifold suction is reduced, the signal strength may 50 drop and to overcome this to an extent, a "suction storage" tank 30 may be introduced in the suction line and a check valve 31 may be provided between this tank and the manifold to hold the "vacuum" in the tank when the 55 manifold pressure rises above that of the tank.

The notes emitted by the instrument constructed as disclosed are clear and harmonious having a true "musical" value and at the same time are loud enough to serve as a good warning signal. The valve mechanism may be controlled arbitrarily by hand, or if desired, the valves may be opened and closed automatically to reproduce predetermined tunes or sound combinations, a suitable motor for operating the valve mechanism being provided

in the latter instance. The employment of stopped organ pipes enables a more compact structure than if open pipes were used and the double reeds provide double condensation and rarification in each pipe. If desired, a 70 small leak may be permitted, for instance, about the valves so that the reeds will be kept in a tremulous state ready to spring into full vibration as soon as the suction force is opened thereto. The reed chamber or chambers prevent the reeds from becoming bound and the air coupling between the reeds and organ pipes provide the proper loading of the reeds by the pipes. The tuning of the reed chambers to the reeds has the effect of creating a 80 tuned combination with the resonators resulting in a maximum sound output from the reeds. The apparatus is relatively simple and inexpensive, can be easily manufactured and readily connected in operative relation on 85 automobiles, motor-boats and other vehicles.

Various means may be provided for operating the valves, for example, electromagnets may be employed such as the solenoids shown at 30 in Figs. 6 and 7 controlled by switches 90 31 and having their cores 32 connected with spring closed shutters 33 governing flow of atmospheric air to the throats of the reeds. It will be evident that when any one of these magnets is energized, air will be induced past 95 the reed at that particular gate or throat and that as soon as the circuit is interrupted, the magnet will be de-energized permitting the spring shutter to slide closed and shut off the air flow. Two or more of the reeds may 100 be simultaneously energized to produce various chime effects. The particular combination of the four notes described, middle A, D, F sharp and treble A is especially desirable as with these notes many different bugle calls 105 and tunes may be sounded.

What is claimed is:

1. A road warning signal for motor vehicles, comprising a suction actuated sound instrument, having a vibrating reed, an amplifying resonator associated therewith to emit a signal of road warning strength, means for connecting said suction operated road warning signal mechanism at will with the intake manifold of the motor of the vehicle, said resonator being tuned to the frequency of the reed and permanently coupled in tuned relation therewith.

2. A road warning signal for motor vehicles, comprising a suction actuated sound instrument, having a vibrating reed and an amplifying resonator associated therewith to emit a signal of road warning strength, means for connecting said suction operated road warning signal mechanism at will with the intake manifold of the motor of the vehicle, the reed having a reed chamber tuned to the frequency of said reed.

3. A road warning signal for motor vehicles, comprising a suction actuated sound in-

- strument, having a vibrating reed and an amplifying resonator associated therewith to emit a signal of road warning strength, means for connecting said suction operated road warning signal mechanism at will with the intake manifold of the motor of the vehicle, said resonator being tuned to the frequency of the reed and coupled in tuned relation therewith and the reed being associated with a reed chamber tuned to both the frequency of the reed and the resonator.
4. In combination with a motor vehicle, suction operated sound instruments of different tones and connections between said several suction operated sound instruments and the intake manifold of the motor, including valve mechanism by which the different instruments may be selectively coupled one at a time to the intake manifold.
5. In combination with a motor vehicle, suction operated sound instruments of different tones and connections between said several suction operated sound instruments and the intake manifold of the motor, including valve mechanism by which the different instruments may be selectively coupled to the intake manifold, said suction sound instruments being tuned to the notes middle A, D, F sharp and treble A and controllable by the valve mechanism to play a plurality of recognizable tunes.
6. A motor vehicle signal comprising reeds tuned to the frequencies of 435, 580.6, 731.5 and 870 cycles respectively and stopped organ pipes associated therewith and of the same respective natural frequencies and connections for subjecting said reeds to the suction pull of the motor.
7. A road signal for motor vehicles, comprising a plurality of reeds, reed chambers of corresponding frequencies associated with the reeds and resonators of corresponding frequencies in coupled relation with said reeds.
8. A motor vehicle road signal, comprising a reed chamber, means for connecting the same with the intake of the motor, a reed in the bottom of said chamber and an organ pipe in coupled relation to said reed below said reed chamber.
9. In combination with the intake manifold of a motor, reed chambers of different sizes, means for selectively connecting said chambers with the intake manifold, correspondingly tuned reeds in said chambers and correspondingly tuned organ pipes in coupled relation to said reeds.
10. In combination with the intake manifold of a motor, a suction operated reed instrument, connecting means between said suction operated reed signal instrument and the intake manifold including control valve mechanism and a suction storage tank.
11. A road signal for motor vehicles, comprising a suction chamber, a sound emitting
- reed mounted therein and connections from said suction chamber to the intake manifold of the motor of the vehicle including a valve block mounted on the suction chamber, said valve block and suction chamber having co-operating port controlling faces by which communication between the motor intake and interior of the suction chamber may be established and means for relatively shifting said valve block and suction chamber to establish or interrupt such communication.
12. A motor vehicle signal, comprising a reed chamber for connection with the intake manifold of a motor, a reed mounted in the base of said chamber, a slide valve mounted on the top of said chamber, said top of the chamber having a port normally opening the interior of the chamber to atmosphere and further having a port for connection with the engine suction, said slide valve overlying said last named port and having a passage to establish inter-communication between the two ports when the valve is shifted to cover both ports.
13. A suction operated instrument for motor vehicles, comprising in combination with the suction intake of a motor, a double-bladed reed, each blade having the same frequency, means for subjecting said double-bladed reed to the action of said suction intake and a resonator associated with said double-bladed reed.
14. A motor vehicle signal, comprising in combination with the suction intake of a motor, a suction operable reed, means for subjecting said reed to the action of said suction intake, an organ pipe in coupled relation with said reed and an exponential horn actuated by said organ pipe.
15. A road signal for motor vehicles, comprising in combination with the suction intake of a motor, a reed having a desired sound frequency, a stopped organ pipe resonator having a frequency corresponding to the frequency of the reed and coupled in resonant relation thereto and means for subjecting said reed to the suction flow of said motor intake.
16. A road signal for motor vehicles, comprising a suction operated reed adapted to be connected with the intake manifold of a motor, so as to be actuated by a suction flow of air and a stopped organ pipe resonator arranged with its open end in resonantly coupled relation to said reed.
17. A road signal for motor vehicles, comprising in combination with a sound reed and means for subjecting the same at will to the suction pull of the motor, a chamber for said reed and a resonator pipe in air coupled relation to the reed and opposed to a wall of the reed chamber.
18. A motor vehicle signal comprising in combination with a motor adapted to create a pressure flow, a double bladed pressure flow

operated reed, the blades of said reed having the same frequency and means for connecting said double bladed reed into the circulation of pressure fluid created by said motor.

5 19. A motor vehicle signal, comprising in combination with a motor adapted to create a flow of pressure fluid, a sounding reed,

means for subjecting said reed to the flow of pressure fluid created by said motor, a resonator in coupled relation to said reed and an exponential horn actuated by said resonator.

In testimony whereof I affix my signature.

JOSEPH L. CASSELL.
